UNITED STATES PATENT OFFICE.

OSCAR R. HOCKS, OF JANEVILLE, WISCONSIN.

HEADLIGHT.

Application filed February 9, 1924. Serial No. 691,623.

To all whom it may concern:

Be it known that I, OSCAR R. HOCKS, a citizen of the United States, and resident of Janesville, in the county of Rock and State of Wisconsin, have invented certain new and useful Improvements in Headlights; and I do hereby declare that the following is a full, clear, and exact description thereof.

10 My invention relates to headlights particularly applicable to motor driven vehicles.

The object of my invention is to provide a simple, effective and economically constructed headlight which will eliminate 15 glare or blinding of a driver facing the lights, but which, at the same time, will produce maximum efficiency with reference to the volume of light.

The specific object of my invention is to 20 provide a horizontally disposed concavo-convex deflector in connection with the light hood, together with other reflector means, for directing the rays of light upwardly against the concavo-convex deflector, whereby 25 by said rays will be broken and indirectly exposed. In other words the light bulb will be at all times concealed from vision of an oncoming driver.

Further objects of the invention are to 30 direct the rays upwardly whereby they are deflected downwardly at a predetermined distance from the vehicle so as to obstruct the vision.

Further objects of my invention are to 35 provide means for concealing the light bulb in connection with means for shifting this concealing blind whereby access may be had for removing or renewing the bulb.

With the above and other objects in view 40 the invention consists in certain practices of construction and invention of parts as will be hereinafter set forth in reference to the accompanying drawings, and subsequently claimed.

45 In the drawings, Figure 1 represents a sectional elevation of a headlight embodying the features of my invention.

Figure 2 represents a cross section of the same the section being indicated by the line 50 2—2 of Figure 1.

Referring by characters to the drawing, 1 represents a standard metallic hood having the usual front glass plate 2. The hood at its rear portion, is formed with a lamp 55 socket 2' which extends obliquely with reference to the curved base of the hood so posi-

tioned that the lamp 3 when fitted to a socket is approximately centrally disposed. The lamp socket is fitted with a semi-circular reflector 4 positioned in axial alignment 60 with the socket. The hood 1 is also provided with a deflector plate 5, the forward portion of which is troughlike in shape. The rear portion of the deflector plate 5 is curved downwardly as shown in Figure 1 and 65 gradually merges into the forward portion thereof. If desired the cylindrical portion of the deflector plate 5 may be tilted forwardly and downwardly a slight extent, for instance the entire headlight may be set so 70 that its axis points slightly downwardly. This deflector is held in place by ribs or lugs 6 which project from the juxtaposed wall of the hood whereby said deflector plate can be readily inserted or removed. The 75 deflector plate is held in position longitudinally by abutting engagement with the rear portion of the hood and forwardly by the glass plate 2.

In order to shield the direct rays of light 80 from the vision of a party in front of the same, I provide a blind 7, the base of which is connected by hinge members 8 to the adjacent inner wall of the hood and approximately in parallel relations with the inclination of the bulb and socket 2'. It is evident that the blind can be adjusted in or out so as to change its angle from a set position, as shown in the drawings, and this 85 change of angle, when effected, is permanently held by set screws 9 which pass through lugs in the blind and frictionally engage the walls of the hood. The upper edge of the blind engages the lower edge of the deflector plate and it is cut downwardly in semi-circular shape to form in conjunction with the deflector plate, a light discharging throat of such area as to meet general requirements. The blind, however, will at all times effectually conceal the light bulb whereby only the 90 reflecting rays of said light bulb are visible.

From the foregoing description it will be manifest that, as indicated by dotted lines, the rays of light will strike the concaved deflector plate which is highly surfaced, and the rays thus reflected will be directed through the throat in a forwardly direction, such throat being formed by the deflector plate 5 and the juxtaposed edge of the blind or baffle plate 7. Thus a full 105 110 volume of light will, at all times, be visible to provide safety when driving at night,

while, at the same time, the danger of blinding oncoming vehicles is entirely eliminated.

While I have shown and described a simple exemplification of my invention in detail, it is understood that I may vary the structural features of it within the scope of the claim and that, obviously, the shape or general design illustrated may be departed from to the taste of the manufacturer.

10 I claim:

A headlight comprising a bell shaped hood, a baffle extending upwardly and forwardly from the bottom portion of said hood and ending a spaced distance from the up-

per portion of said hood, a lamp secured 15 within said hood rearwardly of said baffle plate and projecting upwardly and forwardly, and a deflector mounted within said hood above said baffle plate and having a cylindrical forward portion whose elements 20 approximately parallel the axis of said hood, said cylindrical forward portion gradually merging into a downwardly curved substantially spherical rear portion.

In testimony that I claim the foregoing I have hereunto set my hand at Janesville, in the county of Rock and State of Wisconsin.

OSCAR R. HOCKS.
